UNITED STATES PATENT OFFICE.

FREDERICK P. HOFFMAN, OF UNIONTOWN, PENNSYLVANIA.

TOY GUN.

1,091,512.

Specification of Letters Patent. Patented Mar. 31, 1914.

Application filed May 2, 1913. Serial No. 765,137.

To all whom it may concern:

Be it known that I, FREDERICK P. HOFFMAN, a citizen of the United States, residing at Uniontown, in the county of Fayette, State of Pennsylvania, have invented certain new and useful Improvements in Toy Guns; and I do hereby declare the following to be a full, clear, and exact description of the invention, such as will enable others skilled in the art to which it appertains to make and use the same.

This invention relates to improvements in toy guns.

The principal object is to provide a simple device of this character for projecting pieces of suitable stiff material either for amusement or for advertising purposes, in the latter case, the disk being provided with suitable advertising matter.

Other objects and advantages will be apparent from the following description when taken in connection with the accompanying drawings.

In the drawings: Figure 1 is a perspective view of my gun in position to project a card. Fig. 2 is a vertical longitudinal sectional view showing the arrangement of the projecting arm and the trigger mechanism.

Referring particularly to the accompanying drawing, 10 represents the body of the gun which is formed with a longitudinal slot in its upper side as shown at 11. Pivoted within the outer end of the slot is an arm 12 the free end of which is provided with the side members 13 properly spaced from the arm to provide a slot 14 for the insertion of a card 15. Connected at one of its ends to the inner end of the arm 12 and within the slot 11 is a spring 16, this spring normally tending to draw the arm 14 into projecting position. Projecting through an opening 17 in the rear end of the body and pivoted intermediate its ends

is a trigger member 18, one end of which projects from the rear end of the slot 11 and is formed with a hook 19 for engagement with a laterally extending pin 20 carried by the outer end of the arm 12. The inner end of the trigger 18 projects from the opposite edge and forms a finger grip. The other end of the spring 16 is secured to the trigger member 18, below its pivot, and serves the double function of holding the trigger and actuating the arm 12. A suitable pistol grip 21 is formed on the rear end of the body 10. The arm 12 is drawn back so that the pin 20 engages the hook 19 of the trigger member 18, thus holding the arm back against the tension of the spring 16. Rearward pressure on the finger portion of the trigger moves the outer end forward and releases the arm 12, which flies forward under the influence of the spring 16. The arm 12 strikes against the outer end of the body 10 and projects the card from the slot.

What is claimed is:

A toy gun comprising a body provided with a hand grip, said body having an elongated slot in one side, and an opening therethrough, projector arm pivotally mounted in the slot, a pivoted trigger member mounted in the opening and provided with a hook, a spring secured at its opposite ends respectively to the inner end of the arm and to the trigger, and a pin carried by the outer end of the projector arm for engagement with the hook of the trigger, said projector arm having a card receiving slot in its outer end.

In testimony whereof, I affix my signature, in the presence of two witnesses.

FREDERICK P. HOFFMAN.
